UNITED STATES PATENT OFFICE.

SAMUEL D. MOTT, OF PASSAIC, NEW JERSEY, ASSIGNOR OF ONE-HALF TO ARTHUR B. SULLIVAN, OF ALLENDALE, NEW JERSEY.

AEROPLANE-PROPELLER.

1,361,399.

Specification of Letters Patent.

Patented Dec. 7, 1920.

Application filed April 1, 1916. Serial No. 88,193.

To all whom it may concern:

Be it known that I, SAMUEL D. MOTT, a citizen of the United States, resident of and whose post-office address is 130 Autumn 5 street, in the city of Passaic, county of Passaic, and State of New Jersey, have invented certain new and useful Improvements in Aeroplane-Propellers, of which the following is a description, reference being 10 had to the drawings forming a part hereof.

This invention relates to propellers and more particularly the construction of such peculiarly adapted to meet the conditions of air propellers on aircraft of any sort. The 15 increase of power used for propulsion of aircraft, has been rapid and has necessitated the use of increased sizes of propellers and to absorb the power now used or contemplated in aeroplanes or dirigibles, the limit 20 of strength of the simple propeller blade is being rapidly reached. To secure necessary strength with a blade supported solely by a central hub, the size of hub and butt of the blade increase to a point where the central 25 solid mass presents a substantial resistance.

My construction is intended to meet the new conditions and afford a stronger construction with less central or hub resistance, and to prevent or minimize the deflection of 30 the blade due to the strain incident to the absorption of great power, while affording a lighter construction to meet the operative conditions, also facilitating the manufacture and assembly.

35 A particular form of construction herein-after described, is shown in the accompanying drawings, in which:

Figure 1 is the central portion of a three-blade propeller, the outer portions being 40 broken away.

Fig. 2 is a developed section on the line 2-2 of Fig. 1.

Fig. 3 is a section on the plane in the axis of the propeller.

45 Fig. 4 is a side view of a broken portion of the blade showing modified arrangement of brace connections.

Fig. 5 is an enlarged section of a brace rim.

50 Fig. 6 is a side elevation of half of a three-rim-brace or truss hub.

Fig. 7 is a diagrammatic section at 7-7 of Fig. 6.

In the drawings, A are blades, B is a hub,

C a shaft, D—D are circular braces constituting the rims of skeleton hubs, E is a central brace or rim of a central skeleton hub, F—F are sockets to clamp the circular braces to the propeller. These sockets, as shown in Fig. 2, may involve split ferrules 55 f—f beveled at one end to the obliquity of the blade surface, with nuts f' on suitably threaded portions, not shown, of the circular braces, or the ends of the ferrules f—f may be split and the ends taper-threaded on 60 the outside so that the nuts f' will clamp them tight to the circular braces D and E, with any other suitable locating pins or studs or roughened surface, et cetera, to assist in strengthening and locking of the 65 70 sockets into place.

The circular braces D and E constitute respectively, each the rim of a wire wheel or truss tension wheel structure, and for convenience in further reference these respective wheels may be referred to as D and E, or D when the entire wheel structure is meant, and not only the circular brace. These tension wheels D comprise the hub portions G and the spokes d and d', and in 75 Fig. 3 the spokes d run from the hub collar G to the rim D, and are suitably fastened, as indicated in Fig. 5, by means of nipple and nuts, or are secured in any other suitable manner; while spokes d' run from the rim 80 to the shaft C, thereby carrying the strain 85 direct to the central shaft member. The spokes e—e run from the circular brace E, constituting the rim, to the flanges of the central hub B, while additional spokes e' 90 may be used running directly from the rim normal or directly radial to the central shaft 95 C. In this Fig. 3, the center or butt end of the propeller a is shown as forming a small hub held in place between flanges of the hub B, and the section is taken with illustrator's license in a manner to best serve the purpose of the description, and in like manner the 100 hubs and central shaft are shown in general only, without reference to specific details of construction, which may vary considerably and be made so as to be readily assembled integral or varied in many ways without departing from or modifying the invention, or inventions involved in the whole 105 structure.

In Fig. 1 the spokes d are shown tangential to the central hub B, and indicated as

attaching to the hub lugs in a manner usual in bicycle wheel construction. The spokes *e* in wheel *E*, are shown in this figure radial, but may be combined radial and tangential 5 as desired to suit the particular design and size or strength desired in practice.

In Figs. 6 and 7, it will be seen that lacing or lattice members *H* connect the braces or wheel rims *E* and *D*, while brace *h* or lattice member may connect directly the two lateral circular braces *D*.

In Fig. 1 the wheel rims are attached to the blade by the sockets, as described, the rim being secured about the middle line or 15 axis of the propeller, while *F*—*F*' are secured near the lateral edges of the propeller there being a lateral protuberance on the blade to afford a purchase or anchorage for the sockets *F*', at a lateral distance from 20 the axis of the propeller as great as possible for purposes of strength. In Fig. 4 the shape of the propeller is shown without any such lateral projections, but in Fig. 3 a modification is shown in which the lateral projections *b*' form the steps or brackets for more convenient attachment of the 25 wheels *D*—*D*. As shown in Fig. 2, a sheathing *J* on one side of the propeller may be used to protect the surface, and may be duplicated on the other side for the purpose 30 of preventing the indentation of the sockets, or other fastening members into the material of the propeller when under strain or setting up.

35 It will be seen the truss construction as indicated in Figs. 6 and 7, results in tying together the three circular braces, each one of which is radially tied to afford the greatest rigidity with the lightest weight owing 40 to the character of construction. The three-cornered structure afforded by these rims when tied together gives additional great strength for the weight, and the circular rims as shown, or in any form contemplated 45 afford an exceedingly strong, circumferential structure, and also laterally strong structure at a point considerably removed from the hub center to support the propeller blades and transmit the strain 50 through the skeleton wheels to the hub centers, without the necessity of a large mass of material at the butt end of each blade. If the skeleton hub structure is carried to a point radially where it will support the 55 propeller at the center of reaction, it will be obvious that the strain on the propeller will be substantially balanced on both sides of the point of attachment of the skeleton wheel rim structure. Having the lateral 60 skeleton wheels supported, each edge of the propeller wheel in turn prevents the twisting, or at least minimizes the distortion of the propeller in pitch. The wheel spokes while usually of round wire of great 65 strength, can be made flat or "fish section"

ribbon, thereby affording the minimum resistance of air passing through the hub, and in this manner useful reaction can be taken from the propeller almost from the very center to its tip, instead of housing the large 70 amount of central surface involved in present day construction.

Any suitable means can be used to properly anchor the butt end of the propeller to the central hub, and this may involve a 75 special metal fitting to give support and prevent splitting of the wood or other material of the blade, while still producing a light, practical construction. This also affords the opportunity of making with equal 80 facility individual blades built-up into propellers of two, three or more blades, without the difficulties of matching the hub centers in the present form, and making a very bulky central portion, and with the additional 85 advantage of being able to replace individual blades or avoiding the loss of the entire propeller with the loss of any one blade. Suitable joints may be made in the wheel rims, while the blade sockets may be 90 so constructed as to serve as the junction of the different sections of the wheel rims, for the purpose of assembly. The general assembly can then be readily made and the 95 trueness of the propeller adjusted by proper tensioning or straining of the various lattice members or tangential or radial spokes; as will appear from this disclosure.

In place of the lattice or trussed connections between wheel rims, it will be seen 100 that a flat band or a broad cylindrical rim might be used giving great strength in the direction parallel to the axis of the propeller, and this rim secured to give the necessary torque strength. When so made such 105 cylindrical rim may have openings to fit the section of the propeller and suitable flashing or fittings would then attach the rim to the propeller sides without the severing of the grain of the propeller so as to 110 maintain the maximum transverse or longitudinal strength of the material of the blades.

Various modifications may be made in the structures as herein shown and described, 115 and various details will be added in the practice of my invention beyond the diagrammatic or illustrative drawings filed herewith, all without departing from the spirit of my invention, but what I claim 120 and desire to secure by Letters Patent is:

An aircraft propeller comprising a hub and driving connections, a circular supplementary hub of relatively large diameter and laced to said hub to resist circumferential strain, a second supplementary hub member laced to the hub and laced to the first supplementary hub to resist circumferential strain, a plurality of blades anchored rigidly against circumferential movement 130

on the central hub and means for rigid support in the supplement hub members at a radius less than the effective blade area and having said effective blade area projected 5 clear of all supporting and circumferential strain members.

In testimony whereof, I have signed my

name to this specification, in the presence of two subscribing witnesses, this 28 day of March, 1916.

SAMUEL D. MOTT.
